PERFUME BOX

James Leslie Younghusband, Chicago, Ill., assignor to Les Parfums De Dana, Inc., New York, N. Y., a corporation of New York

Application May 20, 1950, Serial No. 10,071

Term of patent 14 years

(Cl. D58—12)

To all whom it may concern:

Be it known that I, James Leslie Younghusband, a citizen of the Dominion of Canada, residing at Chicago, in the county of Cook, State of Illinois, have invented a new, original, and ornamental Design for a Perfume Box, of which the following is a specification, reference being made to the accompanying drawing, forming part hereof.

In the drawings, Fig. 1 is a perspective front elevational view of a perfume box in closed position embodying my new design; Fig. 2 is a perspective view of the cover; Fig. 3 is a perspective view of the base in open position; Fig. 4 is an edge elevational view; Fig. 5 a top plan view; and Fig. 6 a bottom plan view.

The drawing is shaded to indicate color.

My design is characterized by a diamond shaped box having a diamond shaped cover with a black top and black side walls with gold bands at the top and bottom thereof, and a diamond shaped base whose outer side walls are black and inner side walls are red and having a diamond shaped overlapping platform of gold.

I claim:

The ornamental design for a perfume box, substantially as shown and described.

JAMES LESLIE YOUNGHUSBAND.
